UNITED STATES PATENT OFFICE

1,999,060

SAFETY RAZOR

Gustaf W. Rydner, Detroit, Mich.

Application December 7, 1931, Serial No. 579,517

4 Claims. (Cl. 30—12)

My invention relates to a new and useful improvement in a safety razor and has for its object the provision of a safety razor which will be compact, light, durable, simple in structure, economical to manufacture, easily and quickly assembled and disassembled and possessing a minimum number of parts.

Another object of the invention is the provision of a safety razor so constructed and arranged as to reduce to a minimum and substantially prevent a clogging of the razor when in use.

Another object of the invention is the provision of a safety razor adapted for use with a blade so constructed and arranged as to be highly flexible.

Other objects will appear hereinafter.

The invention consists in the combination and arrangement of parts hereinafter described and claimed.

20 The invention will be best understood by a reference to the accompanying drawing which forms a part of this specification and in which:

Fig. 1 is a perspective view of the invention assembled for use,

25 Fig. 2 is a side elevational view of the invention showing the parts in separated relation,

Fig. 3 is a sectional view taken on line 3—3 of Fig. 2,

30 Fig. 4 is a fragmentary enlarged sectional view,

Fig. 5 is a view taken on line 5—5 of Fig. 2, and

Fig. 6 is a plan view of the blade used with the invention.

It is preferred to form the parts of the razor with the exception of the blade from a moulded material which will be light and which may be of various colors such as the well-known bakelite or similar fibrous compositions. The handle 11 is formed preferably integral with the guard plate 12 which is provided with a plurality of openings 13 separated by the ribs 14. Projecting inwardly of the openings 13 are teeth 15 which are of less height than the ribs 14. Extending longitudinally of the plate 12 at opposite sides

45 of its center are grooves 16. A backing plate or clamping member 17 is provided with a plurality of spaced prongs 18 at opposite sides, adapted to engage in the grooves 16. The blade 27 is provided with a centrally located slot 18' and adjacent opposite ends of this central slot 18' and on opposite sides thereof are formed slots 19. These slots 19 are so spaced as to receive the prongs 18 and when the blade is positioned on the backing plate 17 with the prongs projected through the slots 19, the backing plate with the

blade mounted thereon may be slid longitudinally of the groove 16 so that the prongs 18 will engage in the grooves and serve to prevent a removal of the backing plate or clamping member 17 from operative relation to the guard 12 by any movement other than a longitudinal slidable movement. By virtue of the location of the slots 18' and 19, the blade is easily flexed to conform to the shape determined by the member 17 and the guard plate 12 so that a highly flexible blade is present and the points of flexing are protected by the backing plate and the guard to afford the desired rigidity in the blade while shaving. As clearly appears in Fig. 4, the ribs 14 engage the under surface of the blade 27 which does not project beyond the end of the guard plate. The teeth 15 are spaced from the under surface of the blade 27 to allow clearance for lather and shavings and an enlarged opening 28 extending longitudinally of the guard plate 12 at opposite edges 20 is positioned so that free passage of lather and shavings from the blade 27 is afforded while in use, thus preventing a clogging of the razor.

It is thus seen that the razor comprises, in addition to the blade, only a pair of separable parts 25 which may be easily and quickly assembled or disassembled. When assembled, the resiliency of the blade 27 will resist slidable movement of these parts so that accidental dislocation of the member 17 relatively to the guard 12 is reduced to a 30 minimum.

By forming the parts from composition material as described, an attractive article may be afforded as color contrasts on the various parts may be employed.

35 While I have illustrated and described the preferred form of construction, I do not wish to limit myself to the precise details of structure shown, but desire to avail myself of such variations and modifications as come within the scope of the 40 appended claims.

Having thus described my invention what I claim as new and desire to secure by Letters Patent is:

1. A safety razor comprising a handle; a head 45 carried by said handle and projecting laterally from one end thereof, said head having at opposite sides of its medial line on its outer face a longitudinally extending groove; a backing plate; and spaced prongs on said backing plate engaging in said grooves for retaining said backing plate on said head.

2. A safety razor comprising a handle; a head on one end of said handle and projecting laterally from opposite sides thereof, the outer face of 55

said head being provided at opposite sides of its medial line with longitudinally extending grooves; a backing plate; spaced prongs projecting from one side of said backing plate on opposite sides 5 of its longitudinal medial line and engageable in said grooves for securing said backing plate on said head.

3. A safety razor comprising a handle; a head carried on one end of said handle and having a 10 plurality of spaced longitudinally extending grooves formed therein; teeth formed on opposite edges of said head; ribs on opposite edges of said head lying between said teeth, said teeth being of less height than said ribs; a backing 15 plate; spaced means on said backing plate engageable in each of said grooves for retaining said backing plate on said head and effecting a

pressing of a blade at its opposite edges against said ribs.

4. A safety razor comprising a handle; a head carried on one end of said handle and having a plurality of spaced longitudinally extending 5 grooves formed therein; teeth formed on opposite edges of said head; ribs on opposite edges of said head extending between said teeth, said teeth being of less height than said ribs; a backing plate; spaced means on said backing plate 10 engageable in each of said grooves for retaining said backing plate on said head and effecting a pressing of a blade at its opposite edges against said ribs, said head having an enlarged opening inwardly of said ribs and below the same. 15
